FOREIGN PATENT DOCUMENTS

CN 302819994 * 5/2014

Primary Examiner — Gino Colan*Assistant Examiner* — Tamara L Hahn(74) *Attorney, Agent, or Firm* — Pearne & Gordon LLP;
J. Gregory Chrisman(57) **CLAIM**

The ornamental design for a turret for telescopic lifter, as shown and described.

DESCRIPTION

FIG. 1 is an enlarged back-right side perspective view of a turret for telescopic lifter, showing the new design;

FIG. 2 is a back-right side-top perspective view thereof;

FIG. 3 is a back-left side-top perspective view thereof;

FIG. 4 is a top view thereof;

FIG. 5 is a bottom view thereof;

FIG. 6 is a front view thereof;

FIG. 7 is a back view thereof;

FIG. 8 is a left side view thereof; and,

FIG. 9 is a right side view thereof.

The broken lines shown in the drawings depict portions of the turret for telescopic lifter that form no part of the claimed design.
